(57) **CLAIM**

The ornamental design for a blotting sponge, as shown and described.

DESCRIPTION

FIG. 1 is a perspective view of a blotting sponge showing the new design;

FIG. 2 is a right side elevational view of the embodiment of FIG. 1;

FIG. 3 is a left side elevational view of the embodiment of FIG. 1;

FIG. 4 is a front elevational view of the embodiment of FIG. 1;

FIG. 5 is a rear elevational view of the embodiment of FIG. 1;

FIG. 6 is a top plan view of the embodiment of FIG. 1; and, FIG. 7 is a bottom plan view of the embodiment of FIG. 1. Surface shading is used to shade FIGS. 1-7 to show clearly the character and contour of all surfaces of the 3-dimensional aspects of the design and form a part of the design sought to be protected.
